[57] **CLAIM**

The ornamental design for a theatre structure, substantially as shown and described.

DESCRIPTION

FIG. 1 is a perspective view showing my new design for a theatre structure;

FIG. 2 is a side elevational view thereof;

FIG. 3 is a side elevational view thereof having a cover portion broken away to show the structure immediately therebehind;

FIG. 4 is a transverse cross-sectional view thereof taken in the direction of arrows 4—4 of FIG. 3.

FIG. 1

FIG. 2

FIG. 3

FIG. 4
